FOREIGN PATENT DOCUMENTS

KR 30-0704428 8/2013

Primary Examiner — Michael A. Pratt*(74) Attorney, Agent, or Firm* — Sterne, Kessler, Goldstein & Fox P.L.L.C.**(57) CLAIM**

The ornamental design for an earbud tip, as shown and described.

DESCRIPTION

FIG. 1 is a top front perspective view of an earbud tip showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the earbud tip that form no part of the claimed design.

The dot-dash broken lines in the figures show boundaries that form part of the claimed design.
